10 Claims. (Cl. 194—9)

This invention relates to a coin indicator, and more particularly to a device for selectively responding to the insertion of either one or two coins of a particular denomination in a coin-receiving slot in a vending machine.

Many electrically operated coin-vending machines are provided with microswitches which are positioned adjacent the coin slots for each denomination acceptable to the vending machine. Each microswitch is provided with an actuating or lever arm which extends inside these slots for engagement and deflection by the inserted coins. This deflection causes the microswitch to momentarily close, thereby actuating the vending machine, either directly through closing a simple on-off switch in a circuit connected to the vending machine, or indirectly by driving a rotary switch whose angular position is related to the amount of money inserted in these coin slots. Such a switch rotates until the proper amount of money is inserted in the machine, at which time it makes a contact which closes a circuit and actuates the vending machine. Such devices are commonly known as accumulators or totalizers.

In either case, changing economic conditions, fluctuating costs of labor and materials, and changes in the nature of the product sold by the vending machine, make it desirable to be able to easily adjust the vending machine to vary the prices charged for the merchandise. Such adjustments are possible to a limited extent in existing equipment by changing the angular position of the hot contact point in the accumulator, or by shorting out or rearranging the connections between the microswitches associated with each coin slot. For example, in vending machines of the type described above which are provided with slots for receiving quarters, dimes, nickels and pennies, it would be a comparatively simple matter to connect the microswitches in a conventional circuit for selectively selling products for 25¢, 10¢, 5¢ or 1¢, or for their sums, 26¢, 30¢, 31¢, 35¢, 36¢, 40¢, and 41¢. On the other hand, it would be much more difficult to adjust such vending machines to sell products for 57¢ or for 82¢ for example, because such a modification would require a fundamental redesign of the circuit.

Similarly, although accumulators are more easily adaptable to adjustments in price, they too have a price ceiling which cannot be exceeded without a fundamental redesign of the circuit, or by providing another enlarged accumulator. Furthermore, although the accumulators can be adjusted, within limits, each adjustment is in increments of 5¢. This is not always satisfactory since price increases of only 1¢ are frequently needed, and anything greater might render the product non-competitive from a price standpoint. More particularly, it often happens that products which sell for 5¢ or 6¢ must be raised to 7¢, or products which sell for 25¢ must be raised to 27¢. This cannot be conveniently done by existing equipment, and it would be uneconomical to go to the expense of completely redesigning this equipment to provide the additional price flexibility.

2

What is needed, therefore, and comprises the principal object of this invention, is a device for conveniently adjusting the prices which a vending machine can charge for the merchandise to permit a greater flexibility and range in them.

A further object of this invention is to provide a modified coin-receiving mechanism for coin-operated vending machines which can be attached to the vending machine without extensive modification, and which greatly enlarges the range of possible prices which the machine can charge for the merchandise.

Still another object of this invention is to provide a modified coin-receiving mechanism for electrically operated vending machines which greatly enlarges the range and number of possible prices the vending machine can charge for the merchandise, and which does not require any modification of the electrical circuit.

Yet another object of this invention is to provide a modified coin-receiving mechanism which can be adjusted in a simple and efficient manner selectively to vary the price of merchandise by one or two cents to change the price from 6 cents to 7 cents or from 7 cents to 6 cents, for example.

Still another object of this invention is to provide a simple, easily constructed, coin-receiving mechanism for electrically operated vending machines which can greatly enlarge the number and range of possible prices which the vending machine can charge for the merchandise.

These and other objects and advantages of this invention will become more apparent when read in the light of the accompanying drawings and specification wherein—

Figure 1 is a front elevational view of the coin-receiving mechanism for an electrical vending machine with one coin slot constructed according to the principles of this invention;

Figure 2 is a side elevational view of the coin-receiving mechanism described above;

Figure 3 is a plan view of the coin-receiving mechanism;

Figure 4 is a rear view taken on the line 4—4 of Figure 2 and looking in the direction indicated;

Figure 5 is a front elevational view of the coin-receiving mechanism with a microswitch removed to disclose the weighted support member in supporting position;

Figure 6 is a front elevational view of the coin-receiving mechanism with a microswitch and upper front plate member removed and with the position of the weighted support member in supporting position indicated in dotted lines;

Figure 7 is a front elevational view of the coin-receiving mechanism with the microswitch removed to show the weighted support member in retracted position;

Figure 8 is a front elevational view of the coin-receiving mechanism with a portion of the upper front plate member removed and showing the position of the weighted support member in retracted position in dotted lines; and

Figure 9 is a sectional view taken on the line 9—9 of Figure 5 and looking in the direction indicated.

Referring now to Figure 1 of the drawings, the coin-receiving mechanism indicated generally by the reference numeral 10 comprises a housing 12. The housing consists of a central portion 14 having downwardly extending open-faced coin-receiving slots or channels formed on its opposed sides. These channels include a penny-receiving channel 21, see Figure 3. Front and rear upper plate members 16 and 18 are secured to the upper part of the central portion 14 of the housing, see Figure 2. These plate members act to close the open faces of the coin-receiving channels described above, to restrict the passage of coins therein. The central portion 14 is also provided with a downwardly extending and somewhat rectangular projection 20, see Figures 6

and 8. This projecting portion provides an extension for the nickel-receiving channel 19 and the penny-receiving channel 21 on the opposite sides of the central portion 14. Front and rear lower plate members 22 and 27 are secured to the opposite sides of this projection 20 to close the open faces of the channels therein, see Figure 2.

Associated with each coin-receiving channel, and mounted on these front and rear plate members are a plurality of microswitches, see Figures 1 and 4. These include microswitch 24 which is provided with a coin-sensing or actuating arm 25. This arm is movable between a switch-open and a switch-closed position and is bent perpendicularly to form inwardly projecting step portions. The end portion 26 of this arm penetrates the upper front plate member 16 through an arcuate slot 28 and terminates inside the dime-receiving channel 17, see Figure 3. With this arrangement, when a dime is inserted in the dime-receiving channel 17 through the openings at the top of the housing, it will engage and deflect the actuating arm 25 and force it to the lower edge of slot 28. This in turn will cause the microswitch 24 to close long enough to actuate a relay and a holding circuit (not shown). After the dime passes through the channel 17, the actuating arm 25 is spring-biased back to its rest or circuit open position at the upper edge of slot 28, see Figure 1. The other microswitches associated with the coin-receiving mechanism operate in a similar fashion. In particular, microswitch 30, see Figure 4, is secured to the upper rear plate member 18. This microswitch is also provided with a coin-sensing or actuating arm 32 which is bent perpendicularly to form an inwardly projecting end portion 34, see Figure 3. This end portion penetrates housing 12 through the arcuate slot 36 which extends completely through the housing. Slot 36 also passes through the quarter-receiving channel 15, so when a quarter is inserted therein, the microswitch will be momentarily closed. Another microswitch 38 is secured to the upper rear plate member 18. This microswitch is provided with an actuating arm 40 which is bent to form an inwardly projecting portion 42. This portion penetrates an arcuate slot 44 extending completely through the housing and through the nickel slot 19. The final microswitch 46 is adapted to be actuated by pennies. This microswitch is mounted on the lower front plate 22 and is provided with the usual actuating arm 48. This arm is bent inwardly and penetrates the lower front plate 22 through an arcuate window 50 formed therein, terminating in a U-shaped coin-sensing portion 52, see Figure 9. The base of this portion of the actuating arm 48 rides in a groove 23 in the bottom surface of the penny-receiving channel 21. This is the microswitch which is adapted to be selectively closed by the insertion of either one or two pennies in the penny-receiving channel 21, as will be described below.

The microswitch 24 is mounted on a supporting plate 54, see Figure 1. This supporting plate is bolted to upwardly projecting lug nuts 56 which are integral with the central portion 14 of the housing, and which penetrate openings 58 in the upper front plate member 16, see Figures 7 and 8. An outwardly projecting pivot pin 59 is integral with the upper front plate member 16. A weighted support member acting as a selectively adjustable microswitch-deactivating means, and indicated generally by the reference numeral 60, is provided with a substantially centrally located pivot pin receiving opening 62. This support member is pivotally mounted on pivot pin 59 which penetrates the pivot pin-receiving opening 62. The support member 60 is held on this pivot pin because it is positioned between the upper front plate member 16 and the closely spaced parallel inner surface of the microswitch-supporting plate 54, which thus gives the supporting plate 54 a dual function, see Figure 3. The upper arm 64 of this weighted support member 60 is arcuately curved and is provided with a transverse, in-

tegrally attached, and inwardly projecting coin-sensing or cylindrical abutment member 66, and is also provided with an inwardly projecting limit arm 67. This abutment member 66 penetrates substantially aligned circular openings 69 in the front plate member 16 and in the central portion 14, and extends into the penny-receiving channel 21 for engagement with the pennies inserted therein, see Figures 3 and 7. The upper front plate 16 and the central portion 14 are also provided with aligned openings 63 into which the limit arm 67 projects. This limit arm is adapted to engage the upper and lower edges of the opening 63 when the support member 60 is rotated for restricting its pivotal freedom. The lower arm of this weighted support member 60 is provided with an integrally attached flat metal weight 70 for biasing the support member back to its supporting position when it is momentarily rotated away from it, see Figure 7. The lower end of arm 68 terminates in a flat hook member 72 with a straight work-engaging edge 73. This edge is adapted to engage the coin-sensing portion 52 of the actuating arm 48, and keep it from moving to the circuit closed position when the first penny is inserted in the coin-receiving slot 21, and in addition it causes the coin-sensing portion 52 to obstruct the further passage of the pennies through the housing 12. The upper and lower arms of the weighted support member 60 are so related in size and shape, and the curve of the upper arm is so pronounced, that when a penny encounters abutment member 66 it exerts a force on the support member 60 which is transverse to a radial line extending from its pivotal axis of rotation, and consequently exerts a torque on it which causes it to rotate within the limits defined by the limit slot 63 and the limit arm 67.

A Y-shaped actuating or control lever member 74 is pivotally secured to the upper front plate 16 at 76 by any conventional means such as a rivet. A friction washer (not shown) may be positioned between the lever member 74 and the front plate member 16 to provide a means for holding the lever in place until it is intentionally moved. The lower end 78 of lever 74 is forked to provide spaced abutments. One of the tines 80 of the forked portion 78 is bent perpendicularly so it projects outwardly from the upper front plate member 16. When the control lever 74 is pivoted in the clockwise direction, this tine engages the upper arm 64 of the pivoted support member 60 and forces it to rotate until limit arm 67 moves into engagement with the lower edge of the limit-defining opening 63 in the upper front plate portion 16, see Figure 7. In this position, the hook member 73 of the pivoted support member or microswitch-deactivating means is retracted and moved out of engagement with the U-shaped coin-sensing portion 52 of the actuating arm 48 of the microswitch 46, see Figures 7 and 8. This corresponds to a conventional operation of the coin-sensing mechanism so that each penny inserted in the penny-receiving slot 21 engages the unsupported coin-sensing portion 52 of the actuating arm 48 of the microswitch 46 and moves it so it closes the microswitch. When the Y-shaped control lever 74 is pivoted in the opposite or counter-clockwise direction, its other tine 81 moves into engagement with the lug nut 58 which limits its rotational freedom and provides that lug nut with an additional function, see Figure 5. This movement frees the support member 60 and permits it to rotate back to its supporting position in which the upper edge 73 of the hook member 72 is in supporting engagement with the U-shaped coin-sensing portion 52 of the actuating arm 48 in the penny-receiving channel 21. It is important to note that the force directed against the hook member is along a radial line with respect to the pivotal axis of the support member 60, so that the support member won't rotate because of the force exerted on it by the weight of the penny, as it did when the penny encountered the abutment or coin-sensing member 66, see Figures 5 and 9.

To understand the operation of the coin-receiving mechanism 10, it must first be understood that when any of the microswitches are momentarily closed by the passage of a coin in the slot, either the rotary contact arm of the accumulator is rotated a predetermined amount, corresponding to the amount of money inserted, or in the more simple vending machines which do not require an accumulator, one of the switches in the circuit to the vending machine is made to close. The above-described structure provides a means for causing these microswitches to close just once for the passage of either one or two coins in a coin-receiving slot, and so permits the range of possible prices which can be charged by the vending machine to be expanded.

With the pivoted support member 60 in the position shown in Figures 7 and 8, both the abutment member 66 and the hook member 72 have no effect on the pennies 82 which are inserted in the coin-receiving channel 21 of the coin-receiving mechanism, see Figures 6 and 8. Accordingly, each penny inserted in the slot 21 will engage and deflect the actuating arm 48 on the microswitch 46, momentarily closing that switch as the coin passes out of the coin-receiving mechanism 10 through the exit 84. Rotating the Y-shaped control lever 74 to the position shown in Figure 5, permits the pivoted support member 60 to rotate because of the biasing force exerted by the weight 70. This rotation continues until the edge 73 of the hook member 72 moves back to its supporting position under the rectangular coin-sensing portion 52 of the actuating arm 48 and the limit arm 67 engages the upper edge of opening 63, see Figures 5 and 6. This deactivates the microswitch by preventing the actuating arm from moving when a single penny is inserted in slot 21. Such a penny will move downwardly in the slot until it engages and is stopped by the obstructing rectangular portion 52, see Figure 6.

Whenever a penny is inserted in the coin-receiving channel 21, with the support member 60 in the position shown in Figures 5 and 6, it first encounters the abutment member 66. This encounter deflects the abutment member and pivots the support member 60 out of supporting engagement with the coin-sensing portion 52 of the actuating arm 48 in the penny-receiving channel 21. This movement of the abutment member 66 is sufficient to permit the inserted penny to pass by it and move down the coin-receiving channel 21. After the penny passes the abutment member 66, the biasing force exerted by the weight 70 causes the support member 60 to rotate back to its microswitch-deactivating or arm-supporting position shown in Figures 5 and 6. If the control lever 74 is in the position shown in Figure 5, in which the vending machine is required to charge an extra penny for the merchandise, the support member 60 must return to its supporting position before the first inserted penny encounters the rectangular portion 52 of the actuating arm 48. This requires that the weight of the support member 60 be carefully chosen to keep its inertia down to a minimum. As a further aid, the path of the channel 21 is bent slightly at 83, as shown in Figures 6 and 8, to slow the penny slightly and provide the required time delay, and in addition, the curve in the channel 21 acts to restrict the direction of the force exerted by the penny on the support member to a radial direction so that the pivotally mounted support member will not rotate under that force.

To this point, the microswitch 46 has not closed despite the insertion of the first penny. When, however, the second penny is inserted, its engagement with the abutment member 66 overrides the microswitch-deactivating support member 60 and causes it to rotate out of supporting engagement with the coin-sensing portion 52 of the actuating arm 48. This frees the first inserted penny retained in the slot and permits it to force arm 48 down to close the microswitch 46 as the first inserted penny moves down the channel 21. Because of the mass

of the penny, there is an additional small time delay caused by its inertia, and the frictional resistance it makes with the surface of the channel 21. This additional time delay is sufficient to permit the second inserted penny to catch up with the first one before they leave the exit 84 of the penny-receiving channel 21. This keeps the actuating arm 48 deflected and the microswitch 46 closed until both pennies move out of the penny-receiving slot 21. In this way, it is apparent that by adjusting the actuating or control lever 74, the coin-receiving mechanism can be made to require two coins or pennies in place of one for a single closing of the microswitch 24, and so that price charged for an article selling for 6¢ for example, can be raised to 7¢ or reduced from 7¢ to 6¢ without any further alteration or adjustment of the vending machine.

In the example shown, the apparatus has been applied only to the penny-receiving slot 21 for the purposes of illustration and because increments of a penny in price of articles are very common. It is, of course, obvious that the same modifications could be applied to the other coin-receiving slots in the coin-receiving mechanism in the vending machine for greatly increasing or decreasing the possible prices that the vending machine can accept for the merchandise. For example, suppose each slot had this mechanism attached so either one or two coins of a particular denomination would be required to pass through the mechanism and close the associated microswitch, it would be at once apparent that the maximum price that the vending machine could charge would be doubled or reduced, or in the example described in this case, the maximum price that a vending machine without an accumulator could charge for the merchandise would be raised from 41¢ to 82¢. In addition, the number of possible prices between 1¢ and 82¢ which the machine could charge would be multiplied by a very considerable factor. This is because there are four coin-receiving channels or slots, and each slot could be adjusted to selectively receive either one or two coins. For example, the various actuating or control levers could be adjusted so that the machine requires two quarters, one nickel and two pennies for merchandise selling for 57¢, or these control levers could be adjusted so that the machine required one quarter, two dimes and one penny for articles selling for 46¢, etc. It is again pointed out that all of these changes could be made without making any variation in the electrical circuit. In addition, with reference to a coin-receiving mechanism of the type which drives an accumulator, it is apparent that this modification effectively doubles the capacity of the accumulator without altering its electrical circuit, and in addition, increments of one cent in the price of the merchandise would still be possible.

The invention may be embodied in other forms without departing from the spirit or essential characteristics thereof as set forth in the claims, and the present embodiment is therefore to be considered as illustrative and not restrictive, and it is intended to include all changes which come within the scope and range of the claims.

I claim:

1. A coin-receiving mechanism of the class described, comprising in combination a housing, said housing having at least one downwardly extending coin-receiving slot therein, and circuit closing means associated with said housing, said circuit-closing means provided with an actuating arm movable between a circuit-open position and a circuit-closing position, means biasing said actuating arm to a circuit-open position, said actuating arm having a portion extending into said one coin-receiving slot whereby coins gravitating therethrough are adapted to engage said arm and momentarily move it to its circuit-closing position, a supporting member pivotally mounted on said housing and movable into supporting engagement with said actuating arm so that while the supporting

member engages said actuating arm a coin inserted in said slot is prevented from moving said actuating arm to its circuit closing position and its passage through said coin receiving slot is obstructed by said actuating arm, an abutment member rigidly connected to said supporting member and positioned in said coin receiving slot in upwardly spaced relation to said actuating arm, said abutment member engaged and deflected by each coin inserted in said coin receiving slot so that the supporting member is momentarily moved out of supporting engagement with said actuating arm every time a coin is inserted in said coin receiving slot, biasing means connected to said supporting member to move it back to supporting engagement with said actuating arm after it has been momentarily moved out of supporting engagement with the actuating arm by the insertion of a coin in said coin receiving slot, said coin receiving slot shaped to provide a time delay for the passage of coins therethrough which is sufficient to permit the supporting member which is momentarily moved out of supporting engagement with said actuating arm by the engagement of a first coin inserted in said slot with said abutment member to return it to its supporting position before the first inserted coin can engage and deflect said portion of the actuating arm whereby said first inserted coin is retained in said coin receiving slot, and shaped to permit a second coin next inserted in said coin receiving slot which deflects said abutment member and thereby frees said first coin to move downward in said coin receiving slot and to force said actuating arm to a circuit closing position, to catch up with said first coin in said coin receiving slot to prevent said actuating arm from moving back to its circuit open position before both coins pass entirely through said coin receiving mechanism.

2. The apparatus set forth in claim 1, including means for holding said supporting member out of engagement with said actuating arm so that each coin inserted in said coin-receiving slot engages said portion of said actuating arm and moves it momentarily to its circuit-closing position.

3. The apparatus set forth in claim 1 wherein said supporting member includes upper and lower arms and a substantially centrally positioned pivot pin-receiving opening, said upper arm arcuately curved and provided with a transverse abutment member which projects into said coin-receiving slot inside said housing, said lower arm provided with a laterally projecting and integrally attached weight member for biasing said supporting member to its supporting position, said lower arm terminating in a supporting hook member, said coin-receiving slot shaped so that the force exerted on said supporting member by said retained coin in said coin-receiving slot is directed along a line radial with the pivotal axis of rotation of the supporting member so that the supporting member will not rotate out of supporting engagement when it supports the actuating arm and the weight of the retained coin.

4. A coin-receiving mechanism of the class described, comprising in combination a housing, said housing having at least one downwardly extending coin-receiving slot therein, a microswitch mounted on said housing, said microswitch provided with an actuating arm movable between a switch-open and a switch-closed position, means biasing said actuating arm to a switch-open position, said actuating arm having a portion movably mounted in said housing and extending into said one coin-receiving slot whereby coins of a particular denomination gravitating therethrough are adapted to engage said arm and momentarily move it to its switch closed position, a lever including upper and lower arms pivotally mounted on said housing, the lower arm of said lever provided with a laterally projecting rigidly attached biasing weight member and a support member, said biasing weight member adapted to move said support member into supporting

engagement with said actuating arm so that while the support member engages said actuating arm a coin of said particular denomination inserted in said slot is prevented from moving said actuating arm to its switch closed position and its passage through said coin receiving slot is obstructed by said actuating arm, said upper arm upwardly inclined and provided with a transverse abutment member which projects into said coin receiving slot in said housing for engagement by each coin of a particular denomination gravitating therethrough, said abutment spaced far enough away from the pivotal axis of said lever and positioned so the weight of each coin of said particular denomination inserted in said coin receiving slot and engaging said abutment pivots said lever so said support member temporarily moves out of supporting engagement with said actuating arm, said coin receiving slot shaped so the force exerted on the support member of the lever by the weight of the coin obstructed by said actuating arm is radially directed so that the lever will not rotate and move said support member out of supporting position because of the weight of the obstructed coin, and shaped to provide a time delay for the passage of coins therethrough which is sufficient to permit the support member which is momentarily moved out of supporting engagement with said actuating arm by the engagement of a first coin inserted in said slot with said abutment member to return to its supporting position before the first inserted coin can engage and deflect said portion of the actuating arm whereby said first inserted coin is retained in said coin receiving slot, and shaped to permit a second coin next inserted in said coin receiving slot which deflects said abutment member and thereby frees said first coin to move downward in said coin receiving slot and force said actuating arm to a switch closed position, to catch up with said first coin in said slot and thereby prevent said actuating arm from moving back to its switch open position before both coins pass entirely through said coin receiving mechanism, and a control lever pivotally mounted in said housing, said control lever adapted to be pivoted into engagement with said lever to overcome the biasing force exerted by said weight member and to pivot the lever so the support member is held permanently out of engagement with said actuating arm whereby each coin of said particular denomination inserted in said coin receiving slot engages the unsupported portion of said actuating arm and moves it momentarily to its switch closed position.

5. A coin receiving mechanism of the class described comprising a housing, said housing having at least one downwardly extending coin receiving slot therein, a lever having upper and lower arms pivotally mounted on said housing and movable between a first position where said slot is obstructed and a second position where the slot is not obstructed, the ends of said arms positioned adjacent upper and lower portions of said slot, the upper arm of said lever having an abutment member secured thereto and extending in the upper portion of said slot for engagement with coins of a particular denomination inserted in said slot, said lower arm of said lever provided with biasing means for urging said lever to said first position and a support member, the length of the arms and their position in said slot such that each coin of said denomination inserted in said slot engages said abutment member and overcoming the opposing force exerted by said biasing means pivots said lever arm and moves it to said second position, said pivoting movement sufficient to permit said coin to move past said abutment member and continue downward in the slot while the biasing means returns said lever to its first position, said slot shaped to provide a time delay for the passage of coins of said denomination therethrough which is sufficient to permit the lever which is momentarily pivoted to the second position by the engagement of a first coin inserted in said slot with said abutment

member to return to its first position and cause said first inserted coin to be retained in said slot, and shaped to permit a second coin next inserted in said coin receiving slot which engages said abutment member and pivots said lever to said second position thereby permitting said retained first coin to continue its movement through said slot, to catch up with said first coin before said lever can move back to its first position so that thereafter both coins can move through the slot substantially together.

6. A coin receiving mechanism of the class described comprising a housing, said housing having at least one downwardly extending coin receiving slot, a lever having upper and lower arms pivotally mounted on said housing, the ends of said arms positioned adjacent upper and lower portions of said slot, the upper arm of said lever having an abutment member secured thereto and extending in the upper portion of said coin receiving slot for engagement with coins of a particular denomination inserted in said slot, said lower arm of said lever provided with a laterally projecting rigidly attached weight member and a support member, the length of the arms and their relationship with said slot such that each coin of said denomination inserted in said slot engages said abutment member and overcoming the opposing force exerted by said weight member pivots said lever arm, said pivoting movement sufficient to permit said coin to move past said abutment member and continue downward in its slot while the biasing weight returns said lever to its initial position, and means in said lower portion of said slot movable between a first and second position, said means in said first position positioned to be engaged by coins of said denomination passing through said slot and moved thereby to said second position substantially out of the path of the coins passing through said slot, said means biased toward said first position, the support member of said lever biased into engagement with said means by said attached weight and while in that position, coins of said denomination moving down in said slot engage said means and are obstructed and retained in said slot, said coin receiving slot shaped to provide a time delay for the passage of coins of said denomination therethrough which is sufficient to permit the support member which is momentarily moved out of supporting engagement with said means by the engagement of a first coin inserted in said slot with said abutment member and the consequent pivoting movement of said lever arm, to return to its supporting position before the first inserted coin can engage said means whereby the first inserted coin is retained in said coin receiving slot, and shaped to permit a second coin next inserted in said coin receiving slot which engages said abutment member and causes said supporting member to move out of supporting engagement with said means thereby freeing said first coin to move said means to said second position as it moves down said slot, to catch up with said first coin before said means can move back to its first position so that both coins thereafter move through the remainder of the slot substantially together.

7. The apparatus set forth in claim 6, wherein said slot is shaped so the force exerted on the support member of the lever by the weight of the obstructed coin is radially directed so the lever will not rotate said support out of supporting engagement with said means because of the said weight of the obstructed coin.

8. A coin receiving mechanism adapted to be connected to a vending machine to enable it to be operated, comprising a housing, said housing having at least one coin receiving slot, the width of said slot substantially uniform and substantially equal to the diameter of coins of a particular denomination to permit the passage of said

coins therethrough, actuating means in said housing, said actuating means enabling operation of the vending machine in response to passage of a coin of said denomination through a predetermined portion of said slot, blocking means mounted in said housing and movable between a first and second position, said blocking means in said first position operating to retain coins of said denomination in said slot and prevent their passage past said predetermined portion of said slot, and in said second position permitting every coin of said denomination inserted in said slot to move past said predetermined portion of said slot, coin responsive means connected to said blocking means and operating to temporarily move said blocking means to said second position at least when the second of two coins of said denomination passes through said slot so that both coins of said denomination move past said predetermined portion of said slot together and cause a single movement of said actuating means which enables a vending machine to be operated, and means for permanently holding said blocking means in said second position in said slot so that said actuating means moves to enable a vending machine to be operated each time a coin of said denomination passes through said slot.

9. A coin receiving mechanism of the class described comprising in combination a housing, said housing having at least one coin receiving slot extending therethrough, and circuit closing means mounted in said housing, said circuit closing means having a portion extending into said coin receiving slot and movable therein whereby the passage of a coin of a particular denomination through said slot engages and moves said portion of the circuit closing means and closes a circuit, supporting means mounted in said housing and movable into supporting engagement with the portion of said circuit closing means so it is prevented from moving by the passage of a coin of said particular denomination in said slot and so obstructs and retains said coin in said slot, coin responsive means in said slot, said coin responsive means rigidly secured to said supporting means and operating to temporarily move said supporting means out of supporting engagement with said portion of said circuit closing means whenever coins of said denomination pass through said slot, means biasing said supporting means so it automatically returns to its supporting position after it has been temporarily moved away therefrom, said coin receiving slot shaped to provide a time delay for the passage of a first coin through said slot which is sufficient to permit the supporting means to return to its supporting position and thereby block the passage of a coin of said denomination through said slot, and when a second coin is inserted in said slot to permit the second coin to catch up with the first coin after the supporting means has been temporarily moved out of said slot so that both coins move through a portion of the coin receiving slot together and cause only a single circuit closing movement of the circuit closing means.

10. The apparatus set forth in claim 9 including means for permanently holding said supporting means out of supporting engagement with said portion of said circuit closing means so said portion of said circuit closing means moves to close a circuit each time a coin of said denomination passes through said slot.
